CORE DRILL CONSTRUCTION

Jesse C. Smetherman, Bakersfield, Calif., assignor
to Globe Oil Tools Company, Los Nietos, Calif.,
a corporation of California

Application November 27, 1937, Serial No. 176,859

8 Claims. (Cl. 255—72)

This invention relates to well drilling tools and relates more particularly to a core drill of the wire line type. A general object of this invention is to provide a core drill of the character mentioned that is practical and effective in operation and that is simple and inexpensive to manufacture and service.

Another object of this invention is to provide a wire line core drill embodying novel and very effective means for allowing the inner barrel to retract when hard earth formations are encountered.

Another object of this invention is to provide a core drill of the character mentioned embodying an improved and simplified latch means for retaining the inner barrel in core receiving position in the outer barrel.

Another object of this invention is to provide a core drill of the character mentioned embodying dependable means on the outer barrel for latching the inner barrel in place, the latch means being releasable by a spear type grapple employed to withdraw the inner barrel from the drill when a core has been taken.

A further object of this invention is to provide a core drill of the character mentioned in which the inner barrel is provided with means engageable by a spear lowered into the drilling string on a line or cable for the purpose of removing the inner barrel after the same has received a core.

The various objects and features of my invention will be fully understood from the following detailed description of a typical preferred form and application of the invention, throughout which description reference is made to the accompanying drawings, in which:

Fig. 1 is a longitudinal detailed sectional view of the core drill provided by this invention illustrating the inner barrel in the operative position. Fig. 2 is an enlarged fragmentary vertical detailed sectional view illustrating the latch means and the adjacent parts with the latch means in the normal condition. Fig. 3 is a view similar to Fig. 2 showing a spear holding the latch means released and in lifting engagement with the inner barrel. Figs. 4 and 5 are fragmentary vertical detailed sectional views of the lower portion of the spear with the hooks in their normal positions. Fig. 6 is an enlarged fragmentary vertical detailed sectional view of the core catcher and Fig. 7 is a fragmentary horizontal detailed sectional view taken as indicated by line 7—7 on Fig. 2.

The improved core drill of the present invention includes, generally, an outer barrel 10 car-

rying a cutting head 11, an inner barrel 12 insertable in and removable from the outer barrel 10 and latch means 13 for removably retaining the inner barrel 12 in position to receive a core.

The outer barrel 10 is adapted to be connected with the lower end of a rotary well drilling string S. The barrel 10 is an elongate tubular assembly carrying the cutting head 11 and adapted to receive the core receiving barrel 12. In the preferred construction illustrated the outer barrel 10 includes a top sub 14 provided at its upper end with a threaded pin 15 for connecting with the drilling string S. The longitudinal opening 16 of the top sub 14 constitutes the continuation of the lower end of the opening in the drilling string 15 S. In accordance with the invention an annular downwardly facing shoulder 17 is provided in the sub 14. The shoulder 17 may be provided on the wall of the opening 16 some distance above the lower end of the sub. The outer barrel 10 further includes an intermediate sub 18 threaded to the lower end of the sub 14 and a main barrel section 19 threaded to the lower end of the sub 18.

The cutting head 11 may be threaded on the lower end of a sub 21 which in turn may be threaded to the lower end of the main barrel section 19. The head 11 is a tubular or annular member having a central vertical opening 22. Suitable cutting means are provided on the head 11. In the particular case illustrated in the drawings the cutting head 11 is provided with downwardly and outwardly projecting blades 23 for acting on the earth formation. The blades 23 have parts 24 for trimming the core for reception in the inner barrel 12. The blades 23 are operable to make an annular cut in the earth formation and to leave a core for reception by the inner barrel 12. The circulation fluid usually employed in the rotary method of well drilling is adapted to pass downwardly through the outer barrel 10 and ports 25 are provided in the head 11 for the discharge of the circulation fluid.

The inner barrel 12 is a tubular member or structure adapted to be dropped or lowered through the drilling string S into the outer barrel 10 to receive and retain a core of the earth formation and is adapted to be withdrawn on a line or cable to carry the core to the ground surface. The inner barrel 12 includes a tubular main section 26 adapted to extend longitudinally through the section 19 and the sub 21 when the inner barrel is in position in the drill. A suitable core catcher is provided on the lower end of the inner barrel 12 to grip and retain the core. The core catcher may include a tubular shell 27

threaded on the lower end of the section 26. The shell 21 is provided with an internal flange 28 adjacent its lower end and a floating ring 29 is arranged in the shell 27 between the flange 28 and the lower end of the section 26. Upwardly and inwardly projecting spring fingers 30 are attached to the inner side of the ring 29 to cooperate with the core. In practice there will be vertically spaced rows of spring fingers 30 as illustrated in Fig. 6. The fingers 30 are adapted to permit the free entrance or passage of the core into the inner barrel 12 during the coring operation and are operable to grip and support the core when the inner barrel 12 is withdrawn from the drill. The lower end of the shell 27 is adapted to rest on an internal shoulder 40 of the cutting head 11 to support the inner barrel 12 in its lowermost position.

The inner barrel 12 further includes a head member 31 welded or threaded to the upper end of the main section 26. In the particular case illustrated in the drawings the lower portion of the head member 31 is threaded into the upper part of the section 26. The member 31 is preferably of substantially the same external diameter as the section 26. The member 31 and the section 26 extend through the sub 18 with suitable clearance and the section 26 extends through the outer barrel section 19 with substantial clearance, leaving a continuous annular fluid passage P for conducting the circulation fluid downwardly to the ports 25 in the head 11. The member 31 has a central longitudinal opening 32 communicating with the upper end of the barrel section 26. The lower portion of the opening 32 is reduced in diameter to form or provide an upwardly facing annular shoulder or seat 33. A ball valve 34 is provided in the opening 32 to cooperate with the seat 33. The valve 34 is adapted to seal downwardly against the seat to prevent the downwardly flowing circulation fluid from entering the inner barrel 12 and is adapted to move off its seat 33 when the core entering the inner barrel displaces fluid outwardly through the opening 32. Lateral ports 35 may be provided in the wall of the head member 31 to place the opening 32 in communication with the fluid passage P.

In accordance with the invention an internal flange 36 is provided on the head member 31 above the seat 33. In the preferred construction the flange 36 is annular and is located at the upper end of the member 31 so that its lower end constitutes an annular downwardly facing shoulder 37 adjacent the upper end of the member. The shoulder 37 is preferably inclined downwardly and inwardly relative to the central vertical axis of the tool. The upper portion of the flange 36 is provided with a downwardly and inwardly inclined guide surface 38. The parts are preferably proportioned so that the upper portion of the head member 31 projects into the opening 16 in the sub 14 when the shell 27 rests on the shoulder 40. The upper outer corner 39 of the head member 31 is preferably bevelled off.

The latch means 13 is provided to releasably hold the inner barrel 12 in its core receiving position in the outer barrel 10. The means 13 serves to limit relative longitudinal movement between the barrels 10 and 12 when the drill is operating to cut or obtain a core. In accordance with the invention the latch means 13 is carried by the outer barrel 10 to cooperate with the inner barrel 12. In practice the latch

means 13 may be carried or housed in the top sub 14 of the outer barrel 10. The means 13 includes an upwardly facing abutment in the outer barrel assembly. This abutment may be in the nature of a ring 41 threaded in the opening 16 of the top sub 14 to be in spaced relation to the upper end of the sub 18 and to be spaced below the shoulder 40. The means 13 further includes a shiftable ring 42 and latch dogs 43 carried by the ring 42 to cooperate with the head member 31 of the inner barrel 12. The ring 42 is shiftable vertically or longitudinally in the opening 16 above the abutment ring 41 and the ring 42 serves to limit its downward movement. An annular recess or groove 44 is preferably provided in the upper end of the latch ring 42. The internal diameter of the ring 42 may be substantially the same as that of the abutment ring 41 and may be substantially the same as the diameter of the opening 16 above the shoulder 40. A plurality of circumferentially spaced longitudinal slots 45 is provided in the wall of the ring 42. Pins 46 are welded or otherwise fixed to the ring 42 to pass transversely through the slots 45. The pins 46 pivotally support the latch dogs 43.

The dogs 43 of the latch means 13 normally extend downwardly and inwardly from the slots 45, relative to the longitudinal axis of the tool, to project into the opening or the interior of the ring 42. Stop faces 48 are provided on the dogs 43 to cooperate with the wall of the opening 16 to limit the inward pivoting of the dogs. Notches 47 are provided in the upper or pivoted portions of the dogs 43 and torsional springs 49 are wrapped about the pins 46 in the notches 47 to yieldingly hold the dogs 43 in their active positions where they project downwardly and inwardly in the interior of the ring 42. The springs 49 have their ends reacting against the wall of the opening 16 and the walls of the notches 47 to yieldingly hold the dogs 43 in positions where their inner sides slope downwardly and inwardly relative to the vertical axis of the tool and where their lower ends are substantially horizontal. When the dogs 43 are in the position just mentioned their stop faces 48 engage the wall of the opening 16. The parts are related and proportioned so that the upper end of the head members 31 is slightly below and in parallel opposition to the lower ends of the dogs 43 when the shell 27 of the core catcher rests on the shoulder 40 to support the inner barrel 12.

In accordance with the invention spring means is provided to yieldingly resist relative longitudinal movement between the latch ring 42 and the outer barrel 10. A helical spring 50 is arranged under compression between the shoulder 40 and the upper end of the latch ring 42. The lower end of the spring 50 may be received in the groove 44 and the spring is arranged adjacent or against the wall of the opening 16 so that it does not interfere with the passage of the inner barrel 12 and other equipment through the opening. When the drill is in operation with the inner barrel 12 in position within the outer barrel 10 the engagement of the core with the core catcher fingers 30 and with the barrel 12 may resist downward movement of the inner barrel with the outer barrel so that the lower ends of the fingers 30 cooperate with the upper end of the member 31 to urge the inner barrel 12 downwardly with the outer barrel 10. When very hard earth formation is encountered the resistance to downward movement of the inner

barrel 12 may suddenly increase. If this occurs the spring 50 holding the ring 42 downwardly to resist relative movement between the barrels 10 and 12 yields or gives to remove shock from the inner barrel 12 and the spring 50 acting on the inner barrel 12 through the medium of the ring 42 and the dogs 43 may maintain a yielding downward pressure on the inner barrel 12 to cause it to feed downwardly with the outer barrel 10. When the resistance to downward movement of the inner barrel 12 becomes great the spring 50 may be fully compressed with its convolutions in contact so that the latch means 13 comprising the dogs 43, the ring 42 and the spring 50, serves to definitely limit relative vertical movement between the barrels 10 and 11 and to positively urge the barrel 12 downwardly with the barrel 10.

In accordance with the invention the inner barrel 12 is adapted to be removed from the outer barrel 10 to recover or withdraw the core from the well. The latch means 13 is designed to be released by a spear type tool and the head member 31 of the inner barrel 12 is provided with the shoulder 37 to be engaged by the grappling parts of a spear. In the drawings I have illustrated a spear A for recovering or removing the inner barrel 12 from the core drill. The spear A illustrated in the drawings includes an elongate cylindrical shank 52 whose upper end is adapted to be connected with a wire line or cable (not shown). This line or cable is employed to lower the spear A into the drill stem S and to withdraw the spear from the string 35 after it has obtained a holding engagement with the inner barrel 12. The shank 52 of the spear A is provided at its lower end with a reduced stem 53 provided with a diametric slot 54. The lower end of the slot 54 is preferably closed by a plate 55. A ring 56 surrounds the upper portion of the slotted stem 53 and is welded or otherwise fixed to the stem and the shank 52. A pin 57 is arranged through openings 58 in the ring 56 and the stem 53 to pass transversely through the upper portion of the slot 54. Two oppositely facing dogs 59 are pivoted on the pin 57 to operate in the slot 54. A helical spring 60 is arranged under compression between the opposing inner sides of the dogs 59 to yieldingly urge the dogs outwardly. The ends of the spring 60 may be received in sockets 61 in the dogs 59. The ring 56 confines the upper portions of the dogs 59 to limit their outward pivoting, the lower ends of the dogs 59 are sharpened or pointed and the dogs are barbed or provided with upwardly facing shoulders 62. The shoulders 62 are provided on the outer sides of the dogs 59 and the spring 60 acts on the dogs to normally hold them where they project outwardly from the slot 54. The dogs 59 are adapted to retract into the slot 54.

In the operation of the core drill the outer barrel 10 carrying the cutting head 11 may be operated on the lower end of the drilling string 65 S in the usual manner. When it is desired to obtain a sample or core of the earth formation the inner barrel 12 is lowered or dropped through the string S into the outer barrel 10. The inner barrel 12 is adapted to move downwardly through the subs 14 and 18 to come to the position where the lower end of the shell 27 engages the shoulder 40. During this entrance of the inner barrel 10 the inner barrel contacts the sloping inner sides of the dogs 43 and retracts the dogs so 70 that the dogs do not interfere with the down-

ward movement of the inner barrel. When the inner barrel 12 approaches its final position in the outer barrel 10 the upper end of the head member 31 moves past the dogs 43 and the dogs urged outwardly by the spring 48 automatically return to the positions illustrated in Fig. 2 of the drawings where their lower ends oppose the upper end of the member 31.

The drill is now in condition for operation to obtain a core. As the drill is rotated and fed downwardly in the usual manner circulation fluid is pumped downwardly through the drilling string S to flow through the opening 16, the opening 32, the ports 35 and the passage P to the discharge ports 25 in the head 11. The valve 34 prevents the downwardly flowing fluid from entering the upper end of the inner barrel 12. During the core drilling operation the engagement of the core with the spring fingers 30 and with the interior of the inner barrel 12 may resist downward movement of the inner barrel and the lower ends of the dogs 43 may move downwardly against the upper end of the member 31 to urge the inner barrel downwardly with the outer barrel 10. The spring 50 yieldingly urges the ring 42 downwardly with the outer barrel 10 and acts through the medium of the ring and the dogs 43 to yieldingly urge the inner barrel downwardly with the outer barrel. In the event that hard earth formations are encountered the spring 50 yields to relieve the inner barrel 12 of sudden shock.

When a core of sufficient length has been obtained the spear A is lowered through the drilling string S on a wire line or cable and passes downwardly through the opening 16. The stem 53 is adapted to enter the opening 32 and during the passage of the stem 53 into the opening 32 the pointed ends of the dogs 59 engage the inclined surface 38. This engagement results in retraction of the dogs 59 so that the barbed ends of the dogs pass through the flange 36. When the shoulders 62 pass the flange 36 the dogs 59 spring outwardly so that their shoulders 62 are engageable with the shoulder 37. Substantially simultaneous with the passage of the dogs 59 through the flange 36 the lower end of the ring 56 comes into engagement with the inclined inner sides of the dogs 43 and retracts the dogs into the slots 45. The ring 56 is adapted to retract or move the dogs 43 to positions where the member 31 and the other parts of the inner barrel 12 may move upwardly past the dogs. Fig. 3 of the drawings illustrates the spear A in the position where its dogs 59 have their shoulders 62 in engagement with the shoulder 37 and its ring 56 is in engagement with the dogs 43 to hold them retracted. When the spear is in the position illustrated in Fig. 3 of the drawings it may be pulled upwardly on its wire line or cable to withdraw the inner barrel 12 from the drill. It will be apparent how the shoulders 62 of the dogs 59 cooperating with the shoulder 37 transmit upward movement to the inner barrel 12 so that the inner barrel moves upwardly with the spear A. The bevelled corner 39 of the member 31 moves into engagement with the dogs 43 to retract the dogs as the ring 56 moves upwardly out of engagement with the dogs, and the exteriors of the member 31, the barrel section 26 and the shell 27 engage the dogs 43 to maintain them retracted during the removal of the inner barrel from the well. When the inner barrel 12 is drawn upwardly as just described the spring fingers 30 cooperate with the core to assist in 75

breaking the core free from the earth formation and to trap and support the core so that it is retained in the inner barrel 12 and recovered with the inner barrel. The inner barrel 12 carrying the core is readily pulled upwardly through the drilling string S by the wire line or cable carrying the spear A.

Having described only a typical preferred form and application of my invention, I do not wish 10 to be limited or restricted to the specific details herein set forth, but wish to reserve to myself any variations or modifications that may appear to those skilled in the art or fall within the scope of the following claims.

15 Having described my invention, I claim:

1. In a core drill, an outer barrel, a removable inner barrel in the outer barrel, shiftable latch means in the outer barrel cooperable with the inner barrel, and yielding means resisting upward movement of the latch means in the outer barrel.

2. A well core drill including a tubular outer barrel to be connected with a rotary well drilling string, cutting means on the outer barrel for 25 forming a core, an inner barrel movable through the drilling string and adapted to seat in the outer barrel to receive the core, and releasable means in the outer barrel adapted to yieldingly latch the inner barrel against movement relative 30 to the outer barrel, said releasable means comprising a shiftable spring held member on the outer barrel, and a pivoted latch dog on the member engageable by the inner barrel.

3. A well core drill including a tubular outer 35 barrel to be connected with a rotary well drilling string, cutting means on the outer barrel for forming a core, an inner barrel movable through the drilling string and adapted to seat in the outer barrel to receive the core, an upwardly facing surface on the inner barrel, a latch shiftably supported in the outer barrel and cooperable with the said surface, and spring means carried by the outer barrel resisting upward movement of the latch in the outer barrel and thereby urging the inner barrel to move downwardly with the outer barrel.

4. A well core drill including a tubular outer barrel to be connected with a rotary well drilling string, cutting means on the outer barrel for 40 forming a core, an inner barrel movable through the drilling string and adapted to seat in the outer barrel to receive the core, and means for releasably latching the inner barrel in the outer barrel, comprising a member shiftable in the outer barrel, spring means resisting movement of the member in the outer barrel and a latch on the member cooperable with the inner barrel.

5. A well core drill including a tubular outer barrel to be connected with a rotary well drilling

string, cutting means on the outer barrel for forming a core, an inner barrel movable through the drilling string and adapted to seat in the outer barrel to receive the core, and means for releasably latching the inner barrel in the outer barrel, comprising a member shiftable in the outer barrel, spring means resisting upward movement of the member relative to the outer barrel, and a retractable dog on the member engageable by the inner barrel.

6. A well core drill including a tubular outer barrel to be connected with a rotary well drilling string, cutting means on the outer barrel for 10 forming a core, an inner barrel movable through the drilling string and adapted to seat in the outer barrel to receive the core, and means for releasably latching the inner barrel in the outer barrel, comprising a member shiftable in the outer barrel, spring means resisting upward movement of the member relative to the outer 15 barrel, and a spring urged latch dog on the member retractable by the inner barrel when the same is moved into the outer barrel, the dog having a face engageable by the upper end of the inner barrel when the same is in position in the outer barrel to latch the inner barrel in the outer barrel.

7. A well core drill including a tubular outer barrel to be connected with a rotary well drilling string, cutting means on the outer barrel for 20 forming a core, an inner barrel movable through the drilling string and adapted to seat in the outer barrel to receive the core, and releasable means in the outer barrel adapted to yieldingly latch the inner barrel against movement relative 25 to the outer barrel, said means including a ring shiftable in the outer barrel, a spring in the outer barrel resisting upward movement of the ring therein, and retractable spring urged latch dogs on the ring for cooperating with the inner 30 barrel.

8. A well core drill including a tubular outer barrel to be connected with a rotary well drilling string, cutting means on the outer barrel for forming a core, an inner barrel movable through 35 the drilling string and adapted to seat in the outer barrel to receive the core, releasable means in the outer barrel for latching the inner barrel therein comprising a shiftable spring held member carried by the outer barrel and pivoted latch 40 dogs on the member engageable by the inner barrel and having downwardly and inwardly inclined upper surfaces when in latching engagement with the inner barrel, an internal shoulder on the inner barrel, and a tool operable in the drilling string to engage said surfaces to release the latch dogs and engageable with the shoulder to withdraw the inner barrel from the string.

JESSE C. SMETHERMAN.
